UNITED STATES PATENT OFFICE.

MARTIN VERBEYST, OF PARK RIDGE, NEW JERSEY.

EMBOSSING APPARATUS.

1,093,664.

Specification of Letters Patent. Patented Apr. 21, 1914.

Application filed February 18, 1913. Serial No. 749,561.

To all whom it may concern:

Be it known that I, MARTIN VERBEYST, a citizen of the United States, residing at the borough of Park Ridge, in the county of Bergen and State of New Jersey, have invented certain new and useful Improvements in Embossing Apparatus, of which the following is a specification, reference being had therein to the accompanying drawings, which form a part thereof.

My invention relates to embossing apparatus, and more particularly to a type thereof wherein the raising of the inked surfaces is secured by the application of heat to a printed and prepared sheet of paper.

The main object of the invention is to provide an apparatus wherein substantially the entire surface of the paper will be subjected to the action of a uniform heat of sufficiently high temperature to fuse the resinous composition previously applied to the printed portions of the sheet and combine it with the vehicle of the ink to secure the desired raising of the printed surface, which apparatus will operate at a continuous, comparatively high speed so as to insure capacity in the device and avoid injury to the fiber of the paper.

A further object is to provide an apparatus of this character wherein the feeding and delivery points will coincide so as to permit the operation of the machine by a single operator.

A still further object is to provide an apparatus of this kind wherein the heat will be simultaneously applied to both sides of the paper so as to insure a rapid and thorough fusion of the resinous astringent composition.

A still further object is to provide an apparatus wherein all portions of the printed sheet will be supported in a manner to insure uniform heat conditions about the entire surface of the paper and prevent the accidental destruction or scorching of any portion of the printed sheets. And a still further object is to provide an apparatus of this character which may be economically operated.

The invention consists primarily in an embossing apparatus embodying therein a heating chamber having a closed top and bottom, and side walls, one of which has a reduced opening therein, heating means within said chamber, a circular carrier rotatably mounted adjacent to said heating

chamber and projecting through said opening, the carrying surface of said carrier consisting of a plurality of grids spaced apart radially of said carrier, and means rotating 60 said carrier; and in such other novel features of construction and combination of parts as are hereinafter set forth and described, and more particularly pointed out in the claims hereto appended.

Referring to the drawings:—Figure 1 is a perspective view of an apparatus embodying my invention; Fig. 2 is a side view thereof with the heating chamber shown in cross section; and Fig. 3 is a cross section 70 on an enlarged scale of one of the grid supporting spokes with a section of a grid shown thereon.

Like letters refer to like parts throughout the several views.

In the embodiment of my invention shown in the drawings, *a* indicates a frame supporting a heating chamber, preferably semi-circular in contour and having a closed bottom *b* and closed top *c*, a semi-circular 80 closed side wall *d* and a straight side wall *e* forming a chord to the arc of said side wall *d*. The side wall *e* has a laterally elongated slot *e'* therein, intermediate the bottom *b* and top *c*, and adjacent to the latter. Within the heating chamber are a plurality of ordinary gas burners *f*, so arranged as to secure not only a thorough diffusion of the heat within the chamber, but also uniform application of the heat of these burners 90 to all portions of the carrier. By this means a uniform application of heat to the printed sheet is secured, irrespective of the exact position of the paper upon the carrier, and all sheets will therefore be subjected to 95

substantially uniform conditions while being conveyed through the heating chamber.

Mounted in the frame *a* adjacent the side wall *e*, is a vertical spindle *g* carrying a hub *h* from which a plurality of spokes *i* 100 radiate. Extending circumferentially about this hub *h*, and secured to the spokes *i* are a plurality of annular grids *j*, all positioned in the same horizontal plane and being of varying diameters so as to secure adequate 105 support to a sheet of paper. These grids should be so spaced radially of the spokes *i* as to adapt the machine for use with sheets of paper of different sizes, as it is desirable to hold any sheet upon a horizontal plane 110 and prevent the corners or edges thereof from dropping between the grids where

they might come within the destructive range of the burners *f*. A portion only of the spokes *i* are adapted to project through the opening *e'* into the heating or fusing chamber.

A gridded carrier of the character described exposes the entire upper surface of the paper toward the top of the heating chamber, the inclosing of which portion above the slot *e'* resulting in the maintenance of a high temperature about the printed surface of the paper and thus causing the fusion of the resinous or astringent composition by the direct application of heat as well as the application of heat through the paper itself.

To expose as much of the lower surface of the paper as possible within the heating chamber, I make the spokes *i* triangular in cross section as shown in Fig. 3, and make the grids *j* of comparatively fine wire, preferably round in cross section, thus providing a substantially lineal support for the paper at different points thereof, and preventing the carrier from intercepting any of the heat rising from the burners *f*.

Mounted upon the frame *a* is a speed reducing mechanism comprising a main driving wheel *k*, a worm shaft *k'* actuated thereby, and a worm wheel *k''* upon the shaft *g*. The wheel *k* may be driven from any desired source of power, preferably from the electrical motor *l* mounted upon the frame *a*.

By the driving means described, the carrier is driven continuously at uniform speed, which speed should be determined by the length of time required to thoroughly fuse the resinous or astringent composition at the temperature developed within the heating chamber, and the speed with which the operator may feed the printed and prepared sheets to the machine and remove them therefrom.

A construction such as is heretofore described not only secures compactness of structure and economy in the labor necessary to operate the apparatus, but all sheets passing through the apparatus are acted upon uniformly, thus insuring both capacity in the machine and uniformity in the product.

In addition to the foregoing, I secure by the type of heating chamber and carrier described, a rapid fusing of the resinous and astringent composition, the length of time during which the paper is subjected to the heat within this chamber not being sufficiently great to injure the fibers of the paper itself. In other words, by subjecting the printed and prepared sheets for a short period to a fairly high temperature upon both sides thereof simultaneously, and mainly to diffused heat, the composition to be combined with the vehicle of the ink may be fused without subjecting any portion of

the paper to a continuing temperature which would injure the paper in any way.

The operation of the herein described apparatus is substantially as follows:—The paper is first printed upon with ordinary printers' ink, and after having the resinous astringent in finely comminuted form applied to the printed portions thereof, each sheet is laid face upwardly upon the grids *j*, while the carrier is being continuously rotated. After being laid upon the grids, each sheet is quickly conveyed through the heating chamber, both surfaces thereof being subjected to diffused heat at substantially the same temperature. This action will fuse the resinous astringent compound, and cause it to combine with the vehicle of the ink, raising the printed surface to give the effect of embossed work. Each sheet after passing through the heating chamber, is delivered to the feeder, who removes same and places another sheet in its place.

By having the opening *e'* adjacent the top *e* of the heating chamber, the carrier is spaced away from the burners *f* a sufficient distance to avoid any possibility of the flame impinging upon the paper, or any portion thereof, and at the same time, the heat is given opportunity to diffuse so as to prevent a localized application of the heat to the paper. Furthermore, the spokes *i* being triangular in cross section, will limit the surface thereof adjacent to the paper, and at the same time act as agitators for securing a thorough diffusion of the heated air within the chamber and preventing stratification thereof.

It is not my intention to limit myself to the precise details of construction shown in the accompanying drawings, it being apparent that such may be varied without departing from the spirit and scope of the invention.

Having described my invention, what I claim as new and desire to have protected by Letters Patent, is:—

1. An embossing apparatus embodying therein a heating chamber having a closed top and bottom, and side walls, one portion of which has a reduced opening therein, heating means within said chamber, a circular carrier rotatably mounted exteriorly of and adjacent to said heating chamber, a portion only of said carrier projecting through said opening, the carrying surface of said carrier comprising a plurality of grids spaced apart radially of said carrier, and means rotating said carrier.

2. An embossing apparatus embodying therein a heating chamber having a closed top and bottom, and connecting side walls, one portion of which has a reduced opening therein adjacent to the closed top thereof, heating means adjacent the closed bottom of said chamber, a circular carrier rotatably

mounted exteriorly of and adjacent to said heating chamber, a portion only of said carrier projecting through said opening, said carrier having a surface thereon presented toward the top of said chamber and adapted to receive sheets of paper, whereby said paper is carried through the upper zones of heat in said chamber and subjected to heat from above, and means rotating said carrier.

3. An embossing apparatus embodying therein a heating chamber having a closed top and bottom, and side walls, one portion of which has a reduced opening therein, heating means within said chamber, a circular carrier rotatably mounted exteriorly of and adjacent to said heating chamber, a portion only of said carrier projecting through said opening, the carrying surface of said carrier comprising a plurality of grids spaced apart radially of said carrier, and actuating means for said carrier comprising a rotary shaft, a source of power, and connecting means between said source of power and said shaft whereby said shaft is driven at a continuous, uniform speed.

4. An embossing apparatus embodying therein a heating chamber having a closed top and bottom, and connecting side walls, one portion of which has a reduced opening therein adjacent to the closed top thereof, heating means adjacent the closed bottom of said chamber, a circular carrier rotatably mounted exteriorly of and adjacent to said heating chamber, a portion only of said carrier projecting through said opening, said carrier having a surface thereon presented toward the top of said chamber and adapted to receive sheets of paper, whereby said paper is carried through the upper zones of heat in said chamber and subjected to heat from above, and actuating means for said carrier comprising a rotary shaft, a source of power, and connecting means between said source of power and said shaft whereby said shaft is driven at a continuous, uniform speed.

5. An embossing apparatus embodying therein a heating chamber having a closed top and bottom, and side walls, one portion of which has a reduced opening therein,

heating means whereby the temperature within said chamber is raised, a circular carrier rotatably mounted adjacent to said heating chamber and projecting through said opening, said carrier comprising a plurality of radiating spokes and a series of wires carried by said spokes and spaced apart radially of said carrier, and means rotating said carrier.

6. An embossing apparatus embodying therein a heating chamber having a closed top and bottom, and side walls, one portion of which has a reduced opening therein, heating means whereby the temperature within said chamber is raised, a circular carrier rotatably mounted adjacent to said heating chamber and projecting through said opening, said carrier comprising a plurality of radiating spokes of triangular cross section with the apex presented toward said closed top, and a series of wires carried by said spokes and spaced apart radially of said carrier, and means rotating said carrier.

7. An embossing apparatus embodying therein a heating chamber having a closed top and bottom, and connecting side walls, one portion of which has a reduced opening therein adjacent to the closed top thereof, heating means adjacent the closed bottom of said chamber, a circular carrier rotatably mounted exteriorly of and adjacent to said heating chamber, a portion only of said carrier projecting through said opening, said carrier having a surface thereon presented toward the top of said chamber and adapted to receive sheets of paper, whereby said paper is carried through the upper zones of heat in said chamber and subjected to heat from above, means movable with said carrier for agitating the air within said chamber, and means rotating said carrier.

In witness whereof, I have hereunto affixed my signature, in the presence of two subscribing witnesses, this 15th day of February, 1913.

MARTIN VERBEYST.
